REGISTER CONTROL

Kenneth A. Spearing, Leatherhead, England, assignor to Peabody Engineering Corporation, New York, N. Y., a corporation of New York

Application April 19, 1950, Serial No. 156,871

7 Claims. (Cl. 158—1.5)

1

This invention relates generally to air registers for use with burners for liquid, gaseous or pulverized fuel, although the register may be used for other purposes. It is especially adapted for use with air registers of the same general type as those shown in the patents to Ernest H. Peabody, No. 1,527,214, and to Leslie A. Hicks, No. 2,202,524, both of which show a frusto-conical casing having a plurality of circumferentially arranged rotatable doors by which the admission of air for combustion purposes is controlled. More specifically the invention relates to the mechanism for simultaneously opening and closing the doors of an air register of this general type in varying amounts as desired. While the invention may be used with cylindrical type registers, it is particularly designed and adapted for use with conical type registers.

In the preferred embodiment of the invention, as shown and described herein, each of the doors, when in fully closed position, has a radially outwardly extending bracket secured thereto or formed integrally therewith. These brackets are all connected together by a plurality of individual links, there being one link for each door and bracket. Each link has one end thereof pivotally connected to one bracket and the other end thereof pivotally connected to the adjacent bracket. Each bracket therefore has one end of each of two links connected thereto. In conical registers each bracket moves in a different plane as the doors are opened and closed. This necessitates the connecting of the ends of the links to the brackets in such a manner as to provide in effect a universal connection so that the links may rotate in two different planes. This construction and arrangement is such that when one door is rotated about its axis the motion is transmitted to all the other doors by the linkage so that all of the doors are operated in unison the same amount. A suitable means by which one of the doors is manually operated is provided. A means for locking the doors in adjusted position is also provided.

The principal object of the invention is to provide an improved operating mechanism by which the doors of a conical type register may be operated in unison.

Another object of the invention is to provide an operating mechanism for a register of the above type which comprises a plurality of pivotally mounted links by which the pivoted doors are all connected together to move in unison.

Another object of the invention is to provide an improved connection by which the links in a device of this character are pivotally con-

2

nected to the doors for movement in two different planes.

Still another object of the invention is to provide a mechanism of this character which is efficient in operation, is of simple construction and is inexpensive to manufacture and assemble.

Other and more limited objects of the invention will be apparent from the following specification and the accompanying drawings forming a part thereof wherein:

Fig. 1 is a central vertical section through a conical type air register having my invention incorporated therein, the plane of the section being indicated by the line 1—1 of Fig. 2;

Fig. 2 is a cross section taken on the line 2—2 of Fig. 1;

Fig. 3 is a fragmentary section taken on the line 3—3 of Fig. 4, the scale of which is substantially four times the scale of Figs. 1 and 2;

Fig. 4 is a fragmentary section taken on the line 4—4 of Fig. 3;

Fig. 5 is a view similar to Fig. 3 of a slightly modified form of universal connection between one of the door brackets and a connecting link;

Fig. 6 is a fragmentary section taken on the line 6—6 of Fig. 5; and

Fig. 7 is a fragmentary section taken on the line 7—7 of Fig. 5.

Referring now to the drawings by reference characters, the numeral 1 indicates generally a conical type air register which comprises a front plate 2, a back ring 3, a throat piece 4 and a plurality of adjustably mounted air doors 5. The front plate 2 is secured by bolts 6 to a wind box plate 7, and the inner end of the throat piece 4 is adapted to be suitably secured to the front wall of a furnace (not shown). The back ring 3, which is frusto-conical in shape, has a flared flange 8 formed integral with the larger end thereof. It is supported in spaced relation to the front plate 2, with the smaller end thereof registering with the outer end of the throat piece 4, by a plurality of equally spaced elongated bolts 9 and sleeves 10 which are arranged in an annular row. The bolts 9 extend through the flange 8 of the back ring 3 and an annular flared flange 11 formed on the inner side of the front plate 2. The sleeves 10 are mounted on the bolts 9 between the flanges 8 and 11 and serve to hold the back ring 3 in proper rigid spaced relation to the front plate 2. The air doors 5 are circumferentially arranged and extend between the flanges 8 and 11 with adjacent sides thereof which may or may not overlap when closed, as indicated at 12 in

45

50

55

Fig. 2 to form a closed chamber. The air doors 5 are mounted for swinging movement upon the sleeves 10 by outwardly extending integral flanges 13 at the tops and bottoms thereof, and are adapted to be opened and closed, in varying degrees as desired to admit controlled quantities of air into the air register chamber, by mechanism to be described hereinafter. The front plate 2 is provided with a lighting and inspection opening 14, and a clean-out hole 15. A fuel atomizer barrel 16 is slidably mounted in aligned openings 17 in the ends of a central hub 18 which is formed integral with the front plate 2.

The mechanism by which the air doors 5 are simultaneously opened and closed equal amounts as desired will now be described. Each door 5 has an outwardly extending bracket 20 rigidly secured thereto adjacent the extension 13 at the forward end thereof. The brackets 20 are all connected together by a plurality of links 21, each of which extends between two adjacent brackets 20. Each of the links 21 comprises the central section 22 and the inturned ends 23 which are disposed parallel to each other in the same plane. The ends 23 of the links 21 are connected to the brackets 20 by connectors 24 which provide a universal connection between the links 21 and the brackets 20 so that the links 21 are free to rock in two different planes.

Each connector 24 comprises a head 26 and a shank 27. The shank 27 consists of a smooth cylindrical section 28 and a threaded end 29 of reduced diameter which provides an annular shoulder 30 between the smooth section 28 and the threaded end 29. The smooth cylindrical section 28 is mounted in an aperture 31 in a bracket 20 which is of slightly greater diameter than the diameter of the section 28. The length of the smooth cylindrical section 28 is slightly greater than the thickness of the brackets 20. The connector is held in the aperture 31 by a nut 32 which is screwed onto the threaded end 29 down against the shoulder 30. A lock nut 33 is provided to keep the nut 32 from backing away from the shoulder 30. The head 26 has a bore 34 therethrough, the axis of which intersects and is perpendicular to the axis of the shank 27. The inturned ends 23 of the links 21 are rotatably mounted in the bores 34, and are retained therein by any suitable means such as a split ring 35 mounted in an annular groove 36 at each end of the links 21. The rotatable mounting of the connectors 24 on the brackets 20 together with the rotatable mounting of the inturned ends 23 of the links 21 in the bores 34 of the connectors provide in effect a universal joint between the brackets 20 and the links 21 which permits the links 21 to rock in two different planes. The difference in diameter between the apertures 31 in the brackets 20 and the diameters of the connector shanks 27 compensates for the slight variation in the distance between the opposing connectors on adjacent brackets as the doors are operated.

Any suitable means may be provided for manually operating one of the air doors 5, called the master door, and for locking it in adjusted position. As shown herein one of the sleeves 10, of lesser length than the others, is pinned or otherwise rigidly secured to a shaft replacing bolt 9 as indicated at 40 and the associated door 5 is rigidly secured to the sleeve 10. The shaft is extended out beyond the front of the front plate 2 and has a hand wheel 41 rigidly secured

to the end thereof by which the shaft and the connected sleeve and door may be manually turned as desired. A portion of the extending end of the shaft is threaded as indicated at 42 and has a hand operated locking nut 43 thereon which is adapted to engage an annular shoulder 44 on the front of the plate 2 to lock the shaft and connected door in adjusted position.

In Figs. 5, 6 and 7 I have shown a slightly different means of connecting the links 21 to the doors 5 for rocking movement in two different planes. In this form of the invention I have eliminated the brackets 20 and extended the flanges 13 at the bottoms of the doors as indicated at 45. Functionally the extensions 45 are identical with the brackets 20. To each of the extensions 45 I secure rigidly a pair of connectors 46 instead of the connectors 24. Obviously the connectors 46 could be integral with the extensions 45 if desired. Each connector 46 comprises a bolt having a cylindrical head 47 and a threaded shank 48. The bolt is rigidly secured to an extension 45 by a nut 49 and a locking nut 50. The head 47 has a semi-circular annular groove 51 formed therein, and a collar 52 is rotatably mounted thereon. The collar 52 has a transverse bore 53 therein which intersects the annular groove 51, and has its axis in a plane perpendicular to the axis of the cylindrical head 47. The diameters of the bores 53 and the grooves 51 are preferably the same and are slightly greater than the diameters of the ends 23 of the links 21. The ends 23 of the links 21 are rotatably mounted in the bores 53 of the collars 52 and engage the heads 47 within the grooves 51 as shown in Figs. 5 and 7. The collars 52 are free to rotate on the heads 47 and the ends 23 of the links 21 are free to rotate in the bores 53 of the collars 52, thus providing a connection between the links 21 and the extensions 45 which permits the links 21 to rock in two different planes as the doors 5 are operated. The difference in diameter between the grooves 51 and the bores 53, and the ends 23 of the links 21 compensates for the very slight variation in the distance between the opposing connectors on adjacent doors when the doors are operated.

It should be noted that the same link, connector and bracket arrangement can be used to produce either clockwise or counter-clockwise rotation of the fluid flowing between adjacent doors. If the doors overlap, as shown, in the closed position, a reversal of rotation is accomplished by interchanging, in assembly, the relative position of the overlapping elements of adjacent doors. If the adjacent doors do not overlap in the "closed" position, either direction of rotation can be obtained, and this will depend solely on the direction of rotation of the shaft of the master door as it is caused to move from the "closed" position.

From the foregoing it will be apparent to those skilled in this art that I have provided a very simple, efficient and inexpensive means for accomplishing the objects of my invention.

It is to be understood that I am not limited to the specific construction shown and described herein as various modifications may be made thereto within the spirit of the invention.

What is claimed is:

1. In a register having a plurality of circumferentially arranged peripheral doors mounted to rotate about non-parallel axes and forming a frustum of a cone when closed, means interconnecting said doors for operation in unison comprising a plurality of links, a bracket carried by

each of said doors and extending radially of its axis of rotation, a pair of connectors rotatably secured to each of said brackets with the axes thereof perpendicular to said brackets, each of said links extending between connectors on adjacent doors, and each of said connectors having means connecting the end of a link thereto for rocking movement about an axis lying in a plane perpendicular to the axis of the connector.

2. In a register having a plurality of circumferentially arranged peripheral doors mounted to rotate about non-parallel axes and forming a frustum of a cone when closed, means interconnecting said doors for operation in unison comprising a plurality of links, means including individual connectors connecting the ends of each of said links to two adjacent doors, each of said connectors comprising a pin rotatably secured to a door and having a head with a transverse bore extending therethrough with the axis of said bore in a plane perpendicular to the axis of said pin, the ends of said links being rotatably secured in said bores whereby said links are free to rock about the axis of said bore and about the axis of said pin.

3. In a register having a plurality of circumferentially arranged peripheral doors mounted to rotate about non-parallel axes and forming a frustum of a cone when closed, means interconnecting said doors for operation in unison comprising a plurality of links, means including individual connectors connecting the ends of each of said links to two adjacent doors, each of said connectors comprising a headed bolt rotatably secured to a door and having a transverse bore extending through the head of said bolt with the axis thereof in a plane perpendicular to the axis of said bolt, the ends of said links being rotatably secured in said bores whereby said links are free to rock about the axis of said bore and about the axis of said bolt.

4. In a register having a plurality of circumferentially arranged peripheral doors mounted to rotate about non-parallel axes and forming a frustum of a cone when closed, means interconnecting said doors for operation in unison comprising a plurality of links, a bracket rigidly secured to each of said doors and extending radially of its axis of rotation, a pair of connectors rotatably secured to each of said brackets, each of said links extending between connectors on adjacent doors, and each of said connectors comprising a headed pin rotatably mounted in an aperture in a bracket and having a transverse bore in the head of said pin in which an end of a link is rotatably mounted, the axis of said bore being in a plane perpendicular to the axis of said pin.

5. In a register having a plurality of circumferentially arranged peripheral doors mounted to rotate about non-parallel axes and forming a

frustum of a cone when closed, means interconnecting said doors for operation in unison comprising a plurality of links, a bracket rigidly secured to each of said doors and extending radially of its axis of rotation, a pair of connectors secured to each of said brackets, each of said connectors comprising a headed pin rotatably mounted in an aperture in a bracket and having a transverse bore in the head of said pin the axis of which is in a plane perpendicular to the axis of said pin, each of said links extending between connectors on adjacent brackets and having inturned parallel ends rotatably mounted in the bores of said connectors.

10 6. In a register having a plurality of circumferentially arranged peripheral doors mounted to rotate about non-parallel axes and forming a frustum of a cone when closed, means interconnecting said doors for operation in unison comprising a plurality of links, a bracket rigidly secured to each of said doors and extending radially of its axis of rotation, a pair of connectors secured to each of said brackets, each of said links extending between connectors on adjacent doors, and each of said connectors comprising a headed member rigidly secured in an aperture in a bracket, and means securing said links to the heads of said members for rocking movement in two different planes.

15 7. In a register having a plurality of circumferentially arranged peripheral doors mounted to rotate about non-parallel axes and forming a frustum of a cone when closed, means interconnecting said doors for operation in unison comprising a plurality of links, a bracket rigidly secured to each of said doors and extending radially of its axis of rotation, a pair of connectors secured to each of said brackets, each of said connectors comprising a headed member rigidly secured in an aperture in a bracket, the head of said member being cylindrical and having an annular semi-circular groove formed therein, a collar rotatably mounted on said head and having a transverse bore which intersects said groove, the axis of said bore being in a plane perpendicular to the axis of said member, each of said links extending between connectors on adjacent brackets and having the inturned parallel ends rotatably mounted in the bores in the collars of said connectors.

KENNETH A. SPEARING.
